UNITED STATES PATENT OFFICE.

JOSEPH BENNOR, OF MACON, GEORGIA.

SINKER-ACTUATING MECHANISM FOR KNITTING-MACHINES.

SPECIFICATION forming part of Letters Patent No. 557,640, dated April 7, 1896.

Application filed April 6, 1894. Renewed October 21, 1895. Serial No. 566,415. (No model.)

To all whom it may concern:

Be it known that I, JOSEPH BENNOR, a citizen of the United States, residing at Macon, in the county of Bibb and State of Georgia, have invented certain new and useful Improvements in Sinker-Actuating Mechanism for Knitting-Machines, of which the following is a full, clear, and exact description, reference being had to the accompanying drawings, forming a part of this specification.

This invention relates to the sinker mechanism of that type of knitting-machines wherein two opposite rows of needles are actuated by appropriate cams to effect the knitting of tubular work, the improvement being peculiarly applicable to the sinker mechanism set out in Letters Patent of the United States No. 485,317, granted to me November 1, 1892, to which reference may be had. In the patented construction the oppositely-disposed vibratory sinkers are actuated during each stroke of the knitting-cams by a pair of grooved end-beveled heads, each head having a sliding connection with an adjustable arm extending from the cam-carriage, thereby necessitating the arrangement of the sinkers of one bed laterally of the respective needles of the opposite bed, in consequence of which only coarse goods could be produced.

The object of the improvement is to provide simple and efficient means whereby the sinker-actuating head of each carriage may be moved into and out of action simultaneously with the knitting-cams on that carriage, to the end that the sinkers of one bed may be disposed opposite the needles of the other bed, and in that way permit the construction of a fine-gage machine.

Referring to the drawings, Figure 1 is a vertical section through the needle-beds and cam-carriages of a straight-knitting machine embodying my improvement. Figs. 2 and 3 are under side views of one of the cam-carriages detached, showing the cams in the active and inactive positions, respectively. Figs. 4 and 5 are end and front views, respectively, of Fig. 2. Fig. 6 is a separate view of the slide-bar and frame for controlling the sinker-actuating cam. Fig. 7 is a section, as on the line $x-x$ of Fig. 6.

The oppositely-inclined needle-beds 1 and

2, their needles 3, the reciprocating cam-carriages 4, and their knitting-cams 5 are constructed and operated similarly to the like parts of the machine set out in the said Letters Patent. The vibratory spring-actuated sinkers 6 are likewise alternated with each set of needles; but instead of the two sets of sinkers being operated simultaneously during each stroke of the knitting-cams, only those sinkers on the working side of the machine are actuated. Hence during the knitting of tubular work, as the needles in the respective beds are operated alternately in each reciprocation (two strokes) of the cam-carriages, the two sets of sinkers are alternately active and idle in company with the needles adjacent thereto. In view of this construction the needles of one bed may be arranged to work in paths alternating with those of the other bed, and thus enable the locating of the sinkers of one bed opposite the needles of the other bed. Thus a machine of much finer gage than that of the patented construction may be produced. This part of my invention comprises the means whereby the sinker-actuating cams are supported and controlled. As shown in my patent above referred to, these cams each comprise a grooved end-beveled head D' fitted to a rib d' on the under side of a transverse bar d^2 on the arm d , said head having ample play or lost motion in its traverse to insure its proper position relative to the knitting-cams. In this instance the bar d^2 has sufficient movement in its guideway 7 in the upper section of the cam-carriage to permit the head to be retracted below the cam-engaging portions of the sinkers. A transverse slot 8 is formed in this section of the carriage to receive a block 9 on the upper face of the bar d^2 , the head of the pin 10, which connects the block with the bar, projecting beyond the upper face of said section. The pin-head is fitted to a diagonal groove 13 in the face of a longitudinally-disposed slide-bar 14, the latter in turn being fitted to a frame 15 that is secured to the top of the carriage-section. Hence if the bar 14 be reciprocated, the walls of the groove therein, acting upon the pin, will raise and lower the arm and its connected cam-head, the opposed sides of the frame serving

as determinate stops to limit the movements of the parts. In order that the frame and its connections may be bodily adjusted without changing their relative positions to each other, so as to set the cam-head in proper position in respect to the sinkers, I elongate the holes 16 in the frame through which pass the securing-screws 17. The bars on the respective carriages are actuated at the end of each stroke by means of suitably-disposed stops.

When both sets of knitting-cams are thrown into action at the outstart of the knitting operation, in order to operate both sets of needles simultaneously, the two sinker-actuating cams are retracted; otherwise the simultaneously-moving needles and sinkers of the opposite beds would interfere with each other.

As a means to maintain the slide-bar in either position to which it may be set by its impact with the end stops, I provide a suitable frictional device, which, in this instance, comprises a pin 18, fitted to an orifice in the frame 15 directly above said bar, and a flat spring 19, secured to the frame in a manner to bear upon the pin.

Heretofore during the narrowing and widening operations by the needles on the bed 1 the yarn has been carried in each stroke under the hooks of all the sinkers on that bed.

30 In consequence the yarn conducted beyond the needles in action is "kinked" or "wrinkled" by the pressure of the sinker-hooks, and should there be a knot or irregularity in the yarn thus carried it is apt to catch in the hooks and break the yarn. To obviate this defect, I provide the acting edge of the sinker-actuating head with a recess 20, into which enters the butt of each sinker immediately after it has been drawn back, the sinker-hook 35 thus dropping below the path of the yarn when the yarn is not engaged by the needle. Hence the yarn escapes the sinker at the end of each course of stitches during the fashion-

ing operation, and thus passes freely over the remaining sinkers in its path.

45

I claim—

1. In a knitting-machine, the combination with the needle-beds, the needles, the knitting-cams and the sinkers, of sinker-actuating cams, supports therefor, devices for reciprocating said supports, and means whereby the said supports, the sinker-actuating cams and the reciprocative devices may be bodily adjusted without changing their positions relative to each other, substantially as described. 55

2. The combination with the needle-bed, its needles, the knitting-cams and the sinkers, of a sinker-actuating cam, a sliding support therefor, a slide-bar, provisions whereby it is connected with said support, a frame to 60 which said bar is fitted, and means whereby said frame is adjustably connected with the cam-carriage, substantially as described.

3. The combination with the needle-bed, its needles, the knitting-cams and the sinkers, of a sinker-actuating cam, a sliding support therefor, a slide-bar provided with a diagonal groove therein, a pin extending from said support into the groove, a frame to which said bar is fitted, the inner walls of the frame 70 serving as determinate stops for the pin, and means whereby said frame is adjustably connected with the cam-carriage, substantially as described.

4. The combination with the needle-bed, its needles, the knitting-cams and the sinkers, of a sinker-actuating cam provided with a depression or recess, 20, therein, substantially as described. 75

In testimony whereof I have hereunto affixed my signature in the presence of two subscribing witnesses.

JOSEPH BENNOR.
